RAILWAY MOTOR TRUCK BOLSTER
APPLICATION F LED NOV. 28, 1917.

1,332,588.

Patented Mar. 2, 1920.

2 SHEETS—SHEET 2.

UNITED STATES PATENT OFFICE.

RAYMOND S. ZEITLER, OF CHAMPAIGN, ILLINOIS, ASSIGNOR TO THE ZEITLER GAS CAR & LOCOMOTIVE COMPANY, OF CHICAGO, ILLINOIS, A CORPORATION OF DELAWARE.

RAILWAY-MOTOR-TRUCK BOLSTER.

1,332,588.

Specification of Letters Patent.

Patented Mar. 2, 1920.

Application filed November 28, 1917. Serial No. 204,354.

To all whom it may concern:

Be it known that I, RAYMOND S. ZEITLER, a citizen of the United States, and a resident of Champaign, in the county of Champaign and State of Illinois, have invented a new and useful Railway-Motor-Truck Bolster, of which the following is a specification.

My invention relates to the trucks of rail-way cars wherein a motor such as a gas-engine is incorporated for the purpose of propelling the car. More particularly my invention has reference to the design and construction of the truck bolster employed in a car-truck of this type.

One of the objects of my invention is to so construct the bolster of a standard Master Car Builder's railway car-truck that it may be utilized as the crank case of the gas-engine. Another object is to provide the bolster with means whereby the cylinders of the gas-engine may be secured directly thereto and be supported or sustained thereby. Other objects of my invention are the provision of means whereby the said bolster will be so suspended within the confines of the car-truck that it will meet the Master Car Builder's requirements relating to car-trucks; to provide means whereby a swing-motion may take place without displacement of any of the elements of the truck and engine; to arrange all the parts of the device in a compact manner so that none of the same will be disposed in a horizontal plane above the horizontal plane of the center-bearing; and to construct a bolster that is effective in operation, easy to repair, and comparatively inexpensive to manufacture.

I prefer to accomplish these objects by the means and in the manner hereinafter fully described and as more particularly pointed out in the claims, reference being had to the accompanying drawings forming a part of this specification, in which—

Figure 1 is a longitudinal side elevation of my improved bolster, showing the same applied to a standard railway car-truck.

Fig. 2 is a side view of the car-truck partially in section and partially in elevation, to illustrate the relative construction and location of the bolster and its connected and related parts.

Fig. 3 is a plan view of my bolster detached from the car-truck, a portion of said

bolster being illustrated in section and drawn to an enlarged scale.

Referring to the drawings, similar reference characters are employed to indicate the same parts throughout the various figures.

In Fig. 2 it will be observed the car-truck comprises the usual elements necessary under the requirements of the Master Car Builder's Association and need not be described in detail. The side frame here illustrated is of the cantaliver type, provided with an equalizing bar 5, the ends of which are bent upwardly and laterally to provide means for securing the usual journal boxes thereto. The upper arch bar 7 of the side frame is preferably a horizontally disposed angle beam or other suitable structure, and has strapped thereto the usual flat springs 8, one of the ends of which terminates adjacent the bolster opening and above the plane of the upper arch bar. Suitable depending links 9, 9, are carried by pins *y* mounted in blocks *z* that are adapted to rock at the ends of the springs nearest the bolster and said links have enlargements 10 at their lower ends, through which a transverse pin 11 is adapted to pass, and upon this pin the bolster is supported so as to permit of a swing motion of the latter as will hereinafter more fully appear.

My improved bolster comprises a hollow, composite or built-up structure preferably formed of angle metal and plates, and, as will be observed from the drawings, the central portion of the bolster is substantially 90 rectangular in cross section. The vertical side-walls of the bolster comprise rectangular shaped, elongated plates 12, 13, that have annular flanges 13 at their ends that project both inwardly and outwardly. A flange 95 14 is formed at the upper edges of the side-walls and a top plate 15 is secured to these flanges to connect the side-walls, and at its center said top-plate is provided with the usual center-bearing 16. At the bottom of 100 the side-walls is an inturned flange 17 to which a bottom plate 18 is secured and which connects and forms the box-like structure of the center portion of the bolster.

To the flanges 13 at the ends of the center portion of the bolster are secured intermediate or filler plates 19 that preferably close the ends of the rectangular-shaped portion of the bolster and are provided with a central opening 20, through 110

which a crank-shaft 21 extends. Secured upon the outer surface of these filler plates 19, are substantial cylindrical-shaped end portions 21 that are provided with parallel, 5 laterally disposed suspending lugs 22, upon opposite sides thereof, and through which the pin 11 connecting the links 9 is adapted to pass. These lugs 22 project upon opposite sides of the column guides α of the 10 truck frame to permit the bolster to have a slight longitudinal but limited motion in the manner of the well-known swing motion truck, as well as to have a vertical motion through the action of the springs 8. A 15 dome-shaped or hemispherical, shell-like cap 23 is secured upon and closes the outer ends of the cylindrical-shaped end portions 21 of the bolster and has a screw-threaded opening in its central portion, into which a suitable 20 bearing plate 24 is screwed for providing end-bearing for the adjacent ends of the crank-shaft 21 and which is provided with suitable anti-frictional devices.

Fitted within the cylindrical-shaped portions 21 are suitable round bushings 25 that correspond in dimensions to the inside diameter of said end portions, (the central portion of the bushing 25 is bored out to receive the crank-shaft to which it is keyed 25 by a key 26,) and said bushing is also provided with concentric bores 27 that are utilized as piston chambers in the operation of my bolster when employed in connection with a hydraulic transmission and power device 30 for driving the wheels of the truck, similar to the structure described and illustrated in my co-pending application for Letters Patent of the United States for improvements in a "motor-driven truck for railway cars", 35 filed November 28, 1917, Serial No. 204,355.

As before stated, my improved bolster is adapted to form the crank case of a suitable motor and I have provided upon the side-walls 12 suitable openings 28 around which 45 are secured the cylinders 29 of a suitable engine, preferably a gas or internal combustion engine. The pistons 30 of this engine are adapted to reciprocate in the cylinders 29 and are connected by a connecting rod 50 or pitman 31 with the crank-shaft 21 housed within the bolster.

While I have illustrated and described certain specific instrumentalities for carrying out my invention, it, of course, will be obvious to others, skilled in the art to which my invention pertains, that various modifications or refinements thereof are possible, without materially departing from the spirit of my invention. I, therefore, desire it understood that all such changes are contemplated within the scope of my invention as expressed in the appended claims, and I also

do not wish to be understood as limiting myself to any particular shape or outline of my improved truck bolster. 65

What I claim is:—

1. A combined motor crank case and swing motion truck bolster.
2. A combined motor crank case and hollow swing motion truck bolster.
3. In combination in a car-truck, side-frames, and a combined motor crank case and truck bolster connected at its ends to and suspended from, said side-frames.
4. A combined motor crank case and swing motion truck bolster, provided upon opposite sides, with laterally projecting engine cylinders. 75
5. A hollow swing motion bolster provided with bearings for journaling a crank-shaft therein.
6. A hollow swing motion bolster provided with bearings for journaling a crank-shaft therein, and provided with means for securing engine cylinders thereon. 80
7. A bolster comprising a substantially rectangular shaped central portion, cylindrical end portions secured thereto, and caps mounted upon the outer ends of said end portions. 85
8. A bolster comprising a central portion which is substantially rectangular in cross section and longitudinal section, and end portions secured thereto, provided with bearings for journaling a crank-shaft therein. 95
9. A bolster provided with a central portion that is substantially rectangular in cross section and longitudinal section, an engine cylinder secured to the side-wall thereof, and bearings within said bolster for journaling the crank-shaft of said engine cylinder. 100
10. A bolster provided with a central portion that is substantially rectangular in cross section and longitudinal section, a plurality of engine cylinders secured to the side-walls of said central portion, and bearings within said bolster for journaling the crank-shaft of said engine cylinders. 105

11. A bolster provided with a central portion of substantially rectangular cross section, engine cylinders secured to the opposite side-walls of said central portion, cylindrical extensions for said central portion, and bearings within said extensions for journaling the crank-shaft of said engine cylinders within said bolster. 110

In testimony whereof, I hereunto set my hand and seal this 7th day of May, 1915.

RAYMOND S. ZEITLER. [L.S.]
